UNITED STATES PATENT OFFICE.

GEORGE W. FOSTER, OF VANCOUVER, BRITISH COLUMBIA, CANADA, ASSIGNOR OF FORTY PER CENT TO F. J. RAGLIN, OF COWICHAN LAKE, BRITISH COLUMBIA, CANADA.

FISHING TOOL.

Application filed December 4, 1922. Serial No. 604,862.

To all whom it may concern:

Be it known that I, GEORGE W. FOSTER, a citizen of the United States of America, a resident of the city of Vancouver, in the 5 Province of British Columbia, Canada, have invented certain new and useful Improvements in Fishing Tools, of which the following is a specification.

My invention relates to improvements in 10 fishing tools which has for its objects the provision of suitable means for withdrawing broken drills, rods, cables or casings from bored wells, and which consists essentially of a tube suspended by a bail and 15 having in its side walls a plurality of loosely fitting dogs adapted to fall into contact, during the lowering of the device into the well, with the rod or casing to be withdrawn and to so engage such rod or casing that 20 when an upward movement is imparted to the device the rod or casing is firmly gripped and withdrawn therewith, as will be more fully described in the following specification in which:—

25 Fig. 1 is a sectional view of my invention as in use for withdrawing a broken drill.

Fig. 2 is a sectional view of the device as in use for withdrawing the well casing.

Fig. 3 is a view of the device as in use 30 for engaging a broken cable.

Fig. 4 is an enlarged fragmentary view of a portion of the tube 3 containing a dog holding slot.

Fig. 5 is an enlarged face view of one 35 of the dogs.

In the drawings like characters of reference indicate corresponding parts in each figure.

The numeral 1 indicates a drilled well 40 having a casing 2 forming a lining to the well. 3 is a tube having a bail 4 secured to the upper end by which it is attached to a cable 5 for raising or lowering within the well 1.

45 The numeral 6 (see Figs. 1 and 3) indicates a tubular extension to the tube 3 having a bell shaped mouth 7 of a sufficient diameter to freely enter the well and to direct the shaft of a broken tool into the tube 3, as the device is lowered into contact therewith.

The numeral 8 (see Fig. 2) is a tubular extension to the tube 3 terminating at its lower extremity in a projectile shaped point 50 9 for directing the device clear of any in-

wardly projecting obstructions within the well. The extensions 6 and 8 are interchangeable, either being used upon the tube 3 according to the work required to be done and are preferably attached to the 60 tube 3 by a union 10. 11 (see Fig. 3) is a slot extending longitudinally of the tube 3 and throughout its length which is widened at its lower end to form an inverted V 12, for the purpose of leading a broken cable 65 which may be lying in the well, into position between the dogs 15.

13 indicates a plurality of rectangular apertures cut through the side walls of the tube 3, which are preferably in pairs opposite to each other, 14 (see Fig. 4) is a circular enlargement of the aperture 13 the purpose of which will hereinafter appear.

15 indicates a plurality of dogs which are inserted into the apertures 13, and which 70 are each formed with a curved shank 16 (see Fig. 5), a T head 17 at one end of the shank and a blade 18 at the opposite end, having shoulders 19 and a gripping edge 20. 21 indicates a broken tool rod which it is 80 desired to withdraw from the well.

Having thus described the several parts of my invention, I will now briefly explain its use.

For the purpose of withdrawing a broken 85 rod or cable from the well 1, the dogs 15 are inserted into the apertures 13 of the tube 3 by passing the blade 18 entirely through the aperture and turning the shank portion 16 so that the gripping edge 20 is 90 at right angles to the axis of the tube, so that the blade of the dog is free to swing from a substantially horizontal position to an upwardly inclined angle from the inside 95 of the wall of the tube.

As the device is lowered over the rod, the blade portions of the dogs are raised, the gripping edges sliding downwardly of the rod until a sufficient number of dogs are in engagement therewith, when on an upward pull being exerted upon the device, the dogs bite into the rod producing an effective grip by which the rod is withdrawn from the well.

When using the device for withdrawing a 105 broken cable, the tube 3 having a longitudinal slot 11 is used in conjunction with the tubular extension 6, the device being lowered and rotated simultaneously so that the cable, the free end of which may be lying in close 110

proximity to the casing 2, may be led inwardly into the tube 3 and into engagement with the dogs 15.

When using the device for withdrawing casing, the tubular extension 8 is substituted, and the dogs are set in the apertures with their blades extending outwardly of the tube, that their gripping edges may engage, on the upward lift of the device, with the 10 casing 2 and withdraw it from the well.

It will thus be seen that I have invented a simple and economical device which is powerful in action and which can be relied upon to perform a plurality of functions in 15 removing broken tools and casing from drilled wells.

What I claim as my invention is:

1. In a fishing tool for use in drilled wells, the combination with the tubular body having 20 peripheral slots, a gripping dog extending through each slot and laterally recessed to form integral headed ends engaging the sides of the slot to prevent withdrawal except when the dog is moved to a predetermined position within the slot, and engaging means formed at the end of each dog.

2. A fishing tool of the class described comprising a hollow tube and a plurality of gripping devices carried by the tube and 25 reversible end for end to dispose the grip-

ping portions thereof either interiorly or exteriorly of the tube.

3. A fishing tool of the class described, comprising a hollow tube provided with a plurality of slots and a reversible gripping device for each slot insertable therein to dispose the gripping portion of the device either inwardly or outwardly of the tube.

4. A fishing tool, comprising a hollow tube provided with a slot, a removable gripping device adapted to be pivotally mounted in said slot to dispose the gripping portion thereof either inwardly or outwardly of the tube, said gripping device comprising a narrow shank adapted to pass through the 40 slot and a relatively wide enlargement formed integral with each end of the shank one of said enlargements being provided with a biting edge, the width of said enlargements being less than the length of the 45 slot to permit removal or application of the device when the wide surfaces of the enlargements are disposed in parallel relation to the longitudinal sides of the slot.

Dated at Vancouver this 1st day of 55 November, 1922.

GEORGE W. FOSTER.
